(57) **CLAIM**

The ornamental design for a corrugated foundation drainage tile, as shown and described.

DESCRIPTION

FIG. 1 is a perspective view of a corrugated foundation drainage tile showing our new design;

FIG. 2 is a front elevational view, the rear elevational view being the mirror image thereof;

FIG. 3 is a top plan view, the bottom plan view being the mirror image thereof; and,

FIG. 4 is a right side elevational view, the left side elevational view being the mirror image thereof.
